UNITED STATES PATENT OFFICE.

LILLARD T. MARSHALL, OF WINCHESTER, KENTUCKY.

CHIROPRACTIC TABLE.

1,301,071.

Specification of Letters Patent. Patented Apr. 15, 1919.

Application filed April 24, 1918. Serial No. 230,464.

To all whom it may concern:

Be it known that I, LILLARD T. MARSHALL, a citizen of the United States, residing at Winchester, in the county of Clark and State 5 of Kentucky, have invented certain new and useful Improvements in Chiropractic Tables, of which the following is a specification, reference being had to the accompanying drawings.

10 This invention relates to tables, as they are termed, for use in chiropractic manipulations.

The general object of the invention is to provide a table of this character so constructed that it may be adjusted into a variety of positions permitting of different chiropractic treatments.

15 A further object of the invention is to provide a table which is tiltable from a horizontal to an inclined position.

Still another object is to provide pump operated means for lifting and tilting the table with the patient upon it, said means permitting any desired inclination to be 25 given to the table.

20 A further object is to provide in connection with the tilting table, an adjustable hip supporting cushion, an adjustable shoulder or body supporting cushion, and an abdominal support adjustably connected to the hip supporting cushion.

25 A further object is to provide improved means whereby these various supports may be adjustably mounted and held in adjusted positions.

30 A further object is to provide hip and shoulder supports which are pivotally mounted so that they may be disposed at any desired inclination.

35 40 And still a further object is to improve the details of construction of an appliance of this character, whereby it may be cheaply made and easily adjusted.

45 Other objects will appear in the course of the following description.

My invention is illustrated in the accompanying drawings, wherein:

Figure 1 is a side elevation of my improved chiropractic table;

50 Fig. 2 is a top plan view thereof;

Fig. 3 is a fragmentary side elevation, but showing the table tilted;

Fig. 4 is a section on the line 4—4 of Fig. 1;

55 Fig. 5 is a section on the line 5—5 of Fig. 1;

Fig. 6 is a section on the line 6—6 of Fig. 1;

Fig. 7 is a section on the line 7—7 of Fig. 1;

Fig. 8 is a front end elevation; and

Fig. 9 is a section on the line 9—9 of Fig. 1.

Referring to these drawings, 10 designates the base upon which the table is mounted, 65

and which is provided with the upwardly extending arms 11. Disposed within the base is a piston 12 which is operated by

means of any suitable pedal 13, this piston being slotted at its upper end as at 14. The 70

frame of the table consists of a plurality, preferably two, longitudinally extending angle irons 15. The frame has a horizontal portion *a* for a certain portion of its length, then is upwardly inclined as at *b* and then 75

is again horizontally extended as at *c* and then is upwardly inclined as at *d*. The portion *a* is preferably composed of the two angle irons 15 connected by the angle irons

16 and 17 and from the portion *a* to the portion *d* there are three angle irons, in other 80

words, the two angle irons 15 and a medially disposed angle iron 18 connected at their ends, in any suitable manner, as by the transverse angle iron 19. A weight 20 is mounted 85

in the angular portion *d*, as seen in Fig. 1.

At the end of the frame opposite the angular portion *d*, there are provided the downwardly extending legs 21 carrying the rubber bumpers or feet 22. The several 90

angle irons forming the frame are welded to each other at the joints, so that the frame is practically integral. At opposite sides of the frame, beyond the portion *b*, there are provided the downwardly extended V-shaped 95

members 23, which embrace the upper end of the piston 12 and are pivoted to the piston by a transverse bolt 24 passing through the slot 14. The arms 11 are also pivoted to the frame by means of a transverse bolt 25. 100

It will thus be obvious that as the piston is raised, the frame constituting the table will be tilted until when the piston is raised to its full height, the angular portion *d* of the frame will rest upon the floor, as shown in 105

full lines in Fig. 3. When the piston is lowered to its full extent, the legs 21 will rest upon the floor.

Mounted upon the portion *a* of the frame, are oppositely disposed supporting members, 110

each formed with divergently extending legs 26. These supporting members may be

formed of $\frac{1}{2}$ " strap iron. To these supporting members is pivoted the frame 27 of the shoulder supporting cushion 28. This frame is provided with downwardly projecting ears 29, through which a bolt 30 passes, this bolt extending through the supports 26. Attached to the frame 27 are the arcuate, longitudinally slotted irons 31 and binding screws 32 pass through the corresponding legs 26 and through the slots so that the cushion supporting frame 27 may be tilted to any desired degree and held in its tilting position by rotating the screws 32.

The supporting members 26 are designed 15 to be adjustable along the angle irons 15, and to this end, as illustrated in Fig. 4, the metallic strips forming the members 26 are inwardly extended, as at 33, bent to embrace the inwardly extending flange of the corresponding angle iron 15, then inwardly extended as at 34, and then downwardly extended as at 35. Engaging these downwardly extending ends 35 is a transversely extending screw 36, whose ends are reversely 20 threaded, the screw being provided with a hand wheel. It will be obvious now that by rotating the hand wheel in one direction, the members 26 will be drawn toward each other and that by rotating the hand wheel 25 in the opposite direction, the members 26 will be forced away from each other and into clamping contact with the iron 15. Thus the supporting members 26 may be locked 30 against the angle irons to hold these members 26 in any desired adjusted position.

The hip support comprises a frame 37 carrying the cushion 38 and having ears 39 pivotally connected to supporting members 40, having divergent legs, these legs being 40 of strap iron. The rear pair 40^a of these legs is angularly bent to embrace the inwardly turned flange of the angle irons 15 and attached to the frame 37 is the arcuate member 41 having a longitudinally extending slot, through which passes a binding screw 42 which engages with the corresponding leg 40^a, so that the frame 47 may be inclined to any desired angle.

For the purpose of holding the supporting 50 members 40 in adjusted position upon the frame, the foremost legs 40^b are also bent to embrace the angle irons 15 and then upwardly extended as at 44 and engaged with these upwardly extending ends is the reversely screw-threaded screw 45 having a hand wheel. It will be seen that the manner 55 of holding the supporting members 40 in their adjusted positions is practically the same as that used for the members 26, except that one of the legs 40^b is extended inward sufficiently to rest upon the median angle iron 18.

Disposed between the cushions 28 and 38 is the abdominal support, comprising the 60 frame 46, the cushion 47 and a spring 48,

this spring being curved upward and rearward beneath the cushion 47, the opposite end of the spring extending beneath the frame 37 and being slidably engaged through a metallic strap 49 having a holding screw 50. Thus this abdominal support may be shifted with relation to the hip support.

It will be seen from the foregoing description, and from the drawing, that I have provided a very effective chiropractic table so formed that it may be adjusted into a variety of positions suiting it to any operation which may be performed. It will furthermore be seen that the construction is relatively light, that it is easily manipulated and that the several body supports may be adjusted into a variety of relative positions. The supporting frame upon which the body support is carried, is approximately about 80 6 feet long and approximately 10 inches wide, and when the frame is lowered into the position shown in full lines in Fig. 1, the angle irons 15 will be about $1\frac{1}{2}$ feet from the floor. 90

While I have illustrated certain details of construction and arrangement of parts, yet it will be understood that many changes may be made in these details and in the arrangement of the various parts, without departing from the spirit of the invention as defined in the appended claims. 95

Having described my invention, what I claim is:

1. A chiropractic table including a base, a supporting frame pivotally mounted upon the base, means on the base for shifting the frame into a plurality of angular positions around its pivot, a shoulder support slidably mounted upon the frame and mounted for rotation in a vertical plane, a hip support slidably mounted on the frame and mounted for rotation in a vertical plane, and an intermediate abdominal support, the abdominal support being resiliently mounted upon the hip support for longitudinal adjustment nearer to or farther from the hip support. 10

2. A chiropractic table including a base, a supporting frame pivotally mounted upon the base, means on the base for shifting the frame into a plurality of angular positions around its pivot, a shoulder support slidably mounted upon the base and mounted for rotation in a vertical plane, a hip support slidably mounted on the base and mounted for rotation in a vertical plane, and an intermediate abdominal support, the abdominal support including a spring supporting the abdominal support and extending to and adjustably engaged with the hip support for longitudinal movement whereby the abdominal support may be moved nearer to or farther from the hip support. 11

3. A chiropractic table including a base, a frame mounted upon the base and including 12

longitudinally extending angle irons having inwardly extending flanges, a body supporting member having downwardly extending legs, the legs being formed to embrace the 5 inwardly extending flanges of the angle irons, and a reversely threaded screw engaging the downwardly extended portions of the legs, whereby these legs may be forced into binding engagement with the angle 10 irons or released from said binding engagement.

4. A chiropractic table including a base, a fluid actuated piston mounted in the base, the base having arms extending up to one 15 side of the piston, a body supporting frame pivotally mounted adjacent one end to said arms and pivotally connected to the piston,

that end of the frame adjacent the arms being formed with an angularly disposed foot rest and that end of the frame remote 20 from the arms being provided with legs, and body supporting members individually, longitudinally adjustable on the frame and mounted for angular adjustment in a vertical plane, one of said members carrying a 25 longitudinally adjustable spring extending toward the other member and supporting an abdominal cushion.

In testimony whereof I hereunto affix my signature in the presence of two witnesses. 30

LILLARD T. MARSHALL.
